THE NORRIS PETERS CO., PHOTO-LITHO., WASHINGTON, D. C.

UNITED STATES PATENT OFFICE.

WILLIAM HENRY GUMMERE, OF SOUTH BETHLEHEM, PENNSYLVANIA.

PARTITIONING DEVICE FOR RAILROAD-CARS.

SPECIFICATION forming part of Letters Patent No. 633,835, dated September 26, 1899.

Application filed June 24, 1899. Serial No. 721,702. (No model.)

To all whom it may concern:

Be it known that I, WILLIAM HENRY GUMMERE, of South Bethlehem, in the county of Northampton and State of Pennsylvania, have 5 invented a new and Improved Partitioning Device for Railroad-Cars, of which the following is a full, clear, and exact description.

The invention relates to railroad, express, baggage, and freight cars; and its object is 10 to provide a new and improved partitioning device for forming in a car a separate space for the use of the Government to safely carry packages in bond from one place to another, the device when not in place for the purpose 15 mentioned permitting the free and full use of the entire car by an express or railroad company.

The invention consists of certain parts and details and combinations of the same, as will 20 be fully described hereinafter and then pointed out in the claims.

A practical embodiment of my invention is represented in the accompanying drawings, forming a part of this specification, in which 25 similar characters of reference indicate corresponding parts in all the views.

Figure 1 is a cross-section of a car provided with the improvement. Fig. 2 is a longitudinal section of the same on the line 2 2 in Fig. 1. 30 Fig. 3 is an enlarged sectional side elevation of the improvement. Fig. 4 is a plan view of the same with parts broken out. Fig. 5 is a transverse section of the same on the line 5 5 in Fig. 3. Fig. 6 is an enlarged elevation 35 of the upper locking device. Fig. 7 is a sectional side elevation of the same on the line 7 7 in Fig. 6. Fig. 8 is a sectional plan view of the same on the line 8 8 in Fig. 6. Fig. 9 is an enlarged sectional side elevation of the 40 lower locking device, and Fig. 10 is an edge view of the same.

The car A, in which the improvement is used, is of any approved construction and is provided in its interior at the sides and near the clearstory A' with longitudinally-extending track-rails B, on which are mounted to travel wheeled carriages C, having their frames rigidly connected with each other by a cross-beam D, as is plainly indicated in the drawings. In the ends of the cross-beam D is secured a transversely-extending rod E, on which is mounted to turn a roller F, carrying

a flexible partition G, extending transversely in the car from one side to the other, so as to separate the interior of the car into two compartments, one of which is to be used by the Government for carrying bonded packages and the other may be used by an express or railroad company for other business.

The partition G is formed of flexible strips 60 G', of leather or like material, and cross-bars G², secured to the strips G', are placed a suitable distance apart, as plainly indicated in Fig. 1. The flexible strips G' are attached at their upper ends to pins G³, held in lugs 65 F, formed on the roller F, and the lowermost cross-bar G⁴ of the partition is engaged near its ends by a set of locking devices H, connected with the floor A² of the car, so as to securely hold the partition in place after the 70 carriage C, with the partition, has been shifted lengthwise in the car to the desired place to form a compartment of a desired size, according to the needs of the Government.

The cross-beam D is also adapted to be 75 locked in place after the carriages C have been moved to the desired position by the use of locking devices I, carried on a grate J, rigidly secured to the clearstory A' of the car, it being understood that several such grates 80 J are arranged transversely in the car at different places throughout the length of the rails B to permit of completely separating the two compartments from each other both in the body of the car and in the clearstory A'. 85 It is understood that a set of locking devices H are located directly opposite a grate J, so that the partition G is in complete alinement with the corresponding grate J when the device is used and securely fastened in place. 90 Each locking device H is provided with a member H', straddling the lower cross-bar G⁴ and held in place thereon by a bolt H², extending above the cross-bar, as will be readily understood by reference to Fig. 9. The lower 95 end of the member H' is pivoted on a bolt H³, bolted to the bottom A² of the car. When it is desired to disconnect the locking devices from the partition, it is only necessary to remove the bolt H² to unlock the bar G⁴ from 100 the member H'.

Each of the locking devices I is provided with a transversely-extending member I', riveted or otherwise fastened to a vertical bar

J' of the grate J, (see Figs. 6, 7, and 8,) and in the said member I' is arranged a pivot I² for a vertical member I³, arranged to straddle a cross-bar J² of the grate and the cross-beam D, connecting the carriages C with each other. A bolt I¹ is held in the free end of the member I³ under the cross-beam D, so that when the bolt is in position the cross-beam, and consequently the carriage, with the parts carried thereby, is held against movement on the rails B. Each of the carriages C is also adapted to be locked to the corresponding rail B by a transverse pin C', held on a chain C², carried by the frame of the carriage, the pin C' extending through registering apertures in the carriage and the rail B, as is plainly shown in Figs. 3 and 5.

When the locking devices H are disconnected from the cross-bar G⁴ of the flexible partition G, then the latter may be wound up on the roller F to form an unobstructed clear space in the body of the car at the time the Government is not making use of its compartment for the purpose mentioned, so that the entire car-body can be utilized by the express or railroad company.

In order to conveniently turn the roller F for winding up the flexible partition G, I provide one end of said roller with a sprocket-wheel K, engaged by a sprocket-chain K', dangling downward from the side of the car, so as to be within convenient reach of the operator, and hence when the operator pulls on one run of said chain a rotary motion is given to said sprocket-wheel and to the roller F, so as to wind up the partition G. On one face of the sprocket-wheel K is secured or formed a ratchet-wheel L, engaged by a weighted pawl L', fulcrumed on the corresponding carriage C, to lock said ratchet-wheel, and consequently the sprocket-wheel K and roller F, against return movement.

The ratchet-wheel pawl L' is under the control of the operator, and for this purpose is provided with a downwardly-extending rope I², which when pulled by the operator swings the pawl L' out of mesh with the ratchet-wheel to allow turning of the wheel K and roller F to unwind the flexible partition G, so as to again extend the same transversely in the car from the clearstory to within a short distance of the bottom to divide the car into two compartments, as previously described.

The device may be located near one end of the car or at the middle thereof, and in the latter case the car is preferably provided with two sets of doors to give the proper authorities access to each compartment.

The track-rails B, as shown in Fig. 2, are preferably curved up at the ends, so as to form stops for the carriage when the latter is moved into an end position on said track-rails.

Having thus fully described my invention, I claim as new and desire to secure by Letters Patent—

1. A railroad-car provided in its interior

with an overhead longitudinally-extending track, carriages mounted to travel on the track, and a transverse partition carried by 70 said carriages and adapted to be locked to the car, substantially as shown and described.

2. A railroad-car provided in its interior with a transverse partition arranged to be rolled on an overhead roller, and a fixed grate 75 in the clearstory of the car and in alinement with said partition, substantially as shown and described.

3. A railroad-car, provided in its interior with an overhead longitudinally-extending 80 track, a transverse partition movable on said track, and a fixed grate in the clearstory of the car and in alinement with said partition, substantially as shown and described.

4. A railroad-car, provided in its interior 85 with an overhead longitudinally-extending track, a transverse partition movable on said track, a fixed grate in the clearstory of the car and in alinement with said partition, and means for locking said partition in position 90 in the car, as set forth.

5. A railroad-car, provided in its interior with a longitudinally-movable transverse partition, and a plurality of fixed transverse grates in the clearstory of the car, and locking devices for said partition to lock the latter in place in the car and in alinement with one of said fixed grates, as set forth. 95

6. A railroad-car provided in its interior with an overhead track, carriages mounted to travel on said track, a roller journaled in 100 said carriages, a transverse partition attached to said roller, and means for rotating said roller to wind up or unwind the partition, as set forth.

7. A railroad-car, provided in its interior with an overhead longitudinally-extending track, carriages mounted to travel on said track, a roller journaled in said carriages, and a flexible partition attached to said roller 110 and adapted to be wound thereon and extended therefrom to the bottom of the car, to be locked thereto, substantially as shown and described. 105

8. A railroad-car, provided in its interior 115 with an overhead longitudinally-extending track, carriages mounted to travel on said track, a roller journaled in said carriages, a flexible partition attached to said roller and adapted to be wound thereon and extended 120 therefrom to the bottom of the car, to be locked thereto, a plurality of fixed transverse grates in the clearstory of the car, locking devices for locking said carriages to one of said grates, and locking devices for locking the lower end 125 of the partition to the car at the time the partition is in alinement with one of said grates, as set forth.

9. A railroad-car provided in its interior with a transverse partition, an overhead roller 130 to which said partition is connected, a sprocket-wheel at one end of the roller, a sprocket-chain engaging said roller and extending within reach of the operator, a ratch-

et-wheel on one face of the sprocket-wheel, and a weighted pawl for engaging said ratch-
et-wheel, the said pawl being under the con-
trol of the operator, substantially as set forth.

- 5 10. A railroad-car provided in its interior with an overhead longitudinally-extending track, a transverse partition movable on said track, and locking devices for locking the lower end of the partition to the car, the said
10 locking devices each comprising a member pivotally connected to the bottom of the car,

the free end of said member being bifurcated and arranged to straddle the lower cross-bar of the partition, and a bolt arranged to extend through the free end of said member 15 above the cross - bar, substantially as de-
scribed.
